TRAFFIC CONTROLLING SEMAPHORE

Luis Canepa and Angel Canepa,
Santiago, Chile

Application September 24, 1941, Serial No. 412,178

3 Claims. (Cl. 187—1)

This invention relates to apparatus for the use of police officials in directing vehicular and pedestrian traffic.

The invention has for its object to provide an enclosed platform for supporting the traffic officer in a position suitably elevated to enable him to efficiently discharge his duties and which, when not in use, may be lowered to a concealed position within a shaft and covered so as to present no obstruction in the surface of the pavement or roadway.

A further object of the invention is the provision of means for counterbalancing the weight of the movable parts such as the platform and shaft cover so that these may be manipulated with a minimum of exertion.

In the accompanying drawings wherein an approved form of the invention is illustrated

Figure 1 is a sectional view through a fragment of roadway showing the invention applied to use, the enclosed platform being shown in raised operative position.

Figure 2 is a fragmentary view similar to Figure 1 taken at right angles thereto.

Figure 3 is a portion of Figure 2 showing the locking levers released.

Figure 4 is an enlarged perspective view of the enclosed platform showing the door in open position, and

Figure 5 is a perspective view of the adjustable stop members removed from the bottom of the enclosed platform.

Referring to the drawings in detail, the numeral 10 indicates the surface of a pavement or roadway at or near an intersection where traffic requires the supervision of a directing officer. A vertical shaft 11 of appropriate depth is provided in the roadway and a drain 12, preferably communicating with the sewerage system, is provided in the bottom of the shaft to insure proper drainage of rain water.

The enclosed platform, designated generally by the numeral 13, is mounted for vertical movement in the shaft 11 and when elevated projects a substantial distance above the open top of the shaft. The enclosed platform is constituted by a base 14 supporting the upright side walls 15, one of which designated 16 is hinged at 17 for convenience of access. A perforated floor 18 constituting a support for the occupant, is disposed in spaced relation to the base 14 and the upper part of the enclosure is provided with a rail 19. Immediately below the rail 19 the walls 15 are inclined inwardly and support traffic control

lamps 20, operable by the occupant of the enclosed platform or otherwise.

The base 14 is of such dimensions as to be freely movable through the upper open end of the shaft 11 so as to enable the enclosed platform to be completely removed from the shaft when necessity arises. Normally the upper movement of the enclosed platform is limited by stop members 21 engageable with the overhanging top edges 22 of the shaft whereby the upper movement of the enclosed platform is limited. The stop members 21 are slidably engaged with supporting plates 23 secured to the base 14 and may be moved inwardly with respect thereto so as to permit the entire platform to be withdrawn from the shaft 11. The stop members 21 are provided with bolts 24 engaging in slots 25 provided in the supporting plates 23 and they are secured in adjusted position by wing nuts 26.

The vertical movement of the enclosed platform is guided by a frame 27, preferably of skeleton construction, and provided with a top flange 28 arranged to lie substantially flush with the surface of the roadway surrounding the shaft. At one side of the shaft the flange 28 is provided with a slot 29 receiving the slidably top plate 30 which is movable to a horizontal position for closing the open top of the shaft 11 and for forming a continuation of the surrounding surface 30 of the roadway. To open the shaft and thereby permit the enclosed platform to be moved to raised position, the top plate is swung upwardly to a substantially vertical position and slid downwardly through the slot 29 until it comes to rest upon supporting lugs 31 provided on one side of the guide frame 27. A cable 32 is attached near the free edge of the top plate 30, extends over a guide pulley 33 and is attached at its opposite end to a counterweight 34 whereby the weight of the cover plate is counterbalanced for convenience in the manipulation thereof.

The weight of the entire platform 13 is also counterbalanced by weights 35 attached to cables 36 extending over guide pulleys 37 and attached to the bottom of the enclosed platform. In this manner the weight of the enclosed platform is counterbalanced and the operations of raising and lowering it are simplified.

The enclosed platform is locked in operative raised position by locking levers 38 coacting with stop shoulders 39 attached to the walls of the shaft 11. The locking levers 38 are pivotally secured at 40 adjacent their outer ends to the underside of the base 14 and the inner ends thereof are slotted and engaged with a

pull rod 41 whereby the locking levers may be moved to inoperative position to release the enclosed platform and permit the latter to be lowered. During upward movement of the platform the outer ends of the levers 38 are engaged by the shoulders 39 and tilted in opposite directions, the inner ends of the levers being swung upwardly. When the outer extremities of the levers 38 have passed the shoulders 39 they are swung outwardly by the weight of the inner extremities thereof and being engaged on top of the shoulders 39, support the platform in raised position.

For the protection of the occupant of the enclosed platform a collapsible canopy 42 is supported on the removable upright 43 and, when not in use, the canopy is folded and inserted in a recess 44 provided in the floor 18. The upper extremity of the pull rod 41 passes through one of the perforations in the floor 18 and is provided with a handle 45 for use in releasing the locking levers 38. When not in use the support 43 for the canopy is retained in a holder 46 and a folding seat 47 is attached to one of the side walls 15 for the use of the occupant. The signal lamps 20 may be controlled by the occupant through a manually operable switch 48 and current is supplied for this purpose by means of an electric cable 49. An electric heating unit 50 and a ventilating fan 51 are preferably located in the enclosed platform below the perforated floor 18. The numeral 52 indicates a flag which may be used by the traffic officer in case of failure of the lamps 20.

In operation the shaft is uncovered by lifting the closure plate 30 to an upright position and thereafter lowering it until supported upon the lugs 31. The weights 35 are preferably so proportioned so as to cause the platform 13 to move upwardly to operative position when the shaft is uncovered by opening the plate 30. In moving upwardly the locking plates 38 are deflected by the shoulders 39 and eventually assume a locked position with respect thereto, thus retaining the enclosed platform in raised operative position. The upward movement of the platform is limited by the stop members 21 engaging the overhanging edges 22 of the shaft 11. By opening

the door 16 the traffic officer may have access to the interior of the enclosed platform and during use the door 16 is retained in closed position, as will be understood. When vacating the enclosed platform, the door 16 is opened and the locking levers 38 are released by an upward pull upon the rod 41. The door 16 is subsequently closed and the entire platform is moved to a concealed position within the shaft by the application of a negligible amount of force. Thereafter the closure plate 30 is raised and tilted downwardly to close the open top of the shaft and in this case the top of the plate forms a continuation of the surface of the surrounding roadway.

15 We claim for our invention:

1. An apparatus of the character described comprising a shaft having an open top, an enclosed platform movable from a concealed position within the shaft to a raised position therein, counter-balancing means for said platform, means to lock said platform in raised position, a closure for the open top of said shaft, said top being movable from closed position to an open position disposed substantially parallel with said shaft.

25 2. An apparatus of the character described comprising a shaft having an open top, an enclosed platform movable from a concealed position within the shaft to a raised position therein, counter-balancing means for said platform, means to lock said platform in raised position, and a closure for the open top of said shaft, said locking means including a pair of levers pivoted beneath the platform and movable by gravity to operative position, locking members coacting with said levers and means for moving said levers to inoperative position.

30 3. An apparatus of the character described comprising a shaft having an open top, an enclosed platform movable from a concealed position within the shaft to a raised position therein, counter-balancing means for said platform, means to lock said platform in raised position, and a closure for the open top of said shaft, a base member supporting said platform, and adjustable stop members carried by said base.
